UNITED STATES PATENT OFFICE.

ERNEST ARTHUR THORNTON, OF OMAHA, NEBRASKA.

CLOTHES-DRIER.

No. 864,575.

Specification of Letters Patent.

Patented Aug. 27, 1907.

Application filed September 25, 1905. Serial No. 279,958.

To all whom it may concern:

Be it known that I, ERNEST ARTHUR THORNTON, a citizen of the United States, and a resident of Omaha, in the county of Douglas and State of Nebraska, have 5 invented a new and Improved Clothes-Drier, of which the following is a full, clear, and exact description.

This invention relates to clothes-driers of a style capable of suspension for service from a stable support; and has for its object to provide novel details of construction 10 for a suspensible clothes-drier which are very simple, easily assembled into usable form as a drier, capable of receiving adjustable suspension from the ceiling of a room or other overhead support, so that the drier may be raised or lowered at will; and furthermore, that are 15 adapted for quick detachment from each other so as to permit said parts of the drier to be placed in contact and wrapped together, forming a compact bundle for storage out of the way, when the drier is to be removed from its support.

20 The invention consists in the novel construction and combination of parts as is hereinafter described and defined in the appended claims.

Reference is to be had to the accompanying drawings forming a part of this specification, in which similar 25 characters of reference indicate corresponding parts in all the figures.

Figure 1 is a perspective view of the improved clothes-drier suspended for service, the lowered position therefore when adjusted to permit the suspension of material 30 to be dried being represented by full lines and the elevated position thereof by broken lines; Fig. 2 is an enlarged reversed plan view of the drier-arms and their central supporting head-block; Fig. 3 is a transverse sectional view of details of the drier proper, taken substantially on the line 3—3 in Fig. 2; Fig. 4 is a perspective view of a center block for the bracket frame that supports the drier frame, radial arms extending from the center block being shown in part by dotted lines; Fig. 5 is a transverse sectional view of the means for 35 supporting the drier frame pendent from a ceiling or like support; and Fig. 6 is a sectional side view of a swiveling sheave-block employed, and a portion of the improved drier device secured thereto by means of a screw-eye.

40 In the drawings, 10 represents a block of wood or metal that may be of any suitable form and dimensions, having its normally upper surface grooved, said grooves crossing each other at a right angle, providing the channels *a* and *b*, the latter having double the depth of the channel *a*. In the channels *a* and *b* two similar hanger-bars are embedded, which, of course, cross each other at a right angle and have lapped engagement with each other at their longitudinal centers, thus extending four similar arms 11 radially from the block 10 at equal distances apart at their outer ends.

45 As shown in Fig. 5, a hanger-bolt 12 is cut with a

coarse thread *c* at and near one end for screwing into wood, and a machine cut thread *c'* is formed on the opposite end of the same. The threaded end *c* is screwed into a ceiling *A*, penetrating a solid portion thereof, 60 such as a joist or like timber *A'* that is indicated in transverse section in said figure.

The hanger-bars that constitute the arms 11 are perforated centrally in alinement with a similar perforation *d* in the center block 10, and upon the depending 65 portion of the bolt 12 a washer *e* is strung that seats upon the ceiling *A*; then the arms 11 are engaged with said bolt, that passes thence down through the perforated lower portion of the center block 10 and through a washer *f* thereon, a nut 13, that is screwed 70 upon the threaded projecting lower portion of the hanger bolt, serving, when properly adjusted, to hold the arms and center block securely upon the wall *A*, and at the same time permit rotation of the arms.

The clothes-drier proper comprises a hub 14 that is 75 cylindrical, and upon the hub, near the normally lower end thereof, a radial flange-like enlargement 14^a is formed, as appears in Fig. 3. Below the radial flange 14^a a centrally-apertured clamping plate 15, having a circular edge, is mounted upon a depending 80 end portion of the hub 14. Upon the main or upper portion of the hub 14 another clamping plate 16 is mounted, the hub passing loosely through a central opening of circular form in this plate, and as shown in Figs. 2 and 3, the plates 15 and 16 are secured upon the radial flange 85 14^a by a plurality of bolts 17 and nuts *f'* thereon.

Upon the circular periphery of the upper clamping plate 16 a ring-like flange 16^a is formed or secured, and is thus disposed concentric with the hub 14, it extending down sufficiently to dispose the lower edge thereof 90 in the same plane with the lower surface of the clamping plate 15. In the peripheral flange 16^a a plurality of spaced openings *g* are formed, these openings, of equal dimensions, each having a rectangular defining edge for the reception of a respective one of a number 95 of radial arms 18, as indicated in Figs. 1, 2 and 3. The arms 18 are of considerable length and may taper somewhat from one end to the other, their end portions that enter the openings *g* being neatly fitted therein, and when in place abut at their inner extremities 100 against the hub 14, as shown in Fig. 3.

In Figs. 2 and 3 there is shown an annular flange *h* that is formed upon the lower side of the clamping plate 16 at a suitable distance from the peripheral flange 16^a, and in the upper surface of each arm 18 a notch is 105 formed wherein the annular flange is seated and fits neatly, this engagement being effected after all the arms are inserted previous to the seating of the plate 16 upon the radial flange 14^a.

It will be seen that the clamping adjustment of the 110 bolts 17 and nuts *f'* will secure the arms 18 immovably upon the central hub 14 and clamping plates 15 and 16,

said arms affording support for clothing or other fabric which is to be hung up for free exposure to the air to ventilate and dry the goods, such support being available after the hub, plates and arms are suspended by 5 means that will now be described.

In a central bore in the hub 14 a hanger-bolt 14^b is fitted, which is headed at one end, and provided with a nut *i* or other securing means, at the opposite end thereof which as shown in Fig. 3, may be threaded and 10 project above the upper end of the hub. Upon the projecting upper portions of the bolt 14^b two similar hanger-bars 19 are mounted and disposed at right angles with each other, said bars being of an equal length with the hanger-bars forming the arms 11. Above the bars 15 19 a washer *k* and the nut *i* are mounted on the bolt end 14^b, and the nut is screwed on the end of the bolt, so as to clamp the bars 19 loosely upon the hub 14, thus permitting the arms to rotate on the bolt. A cross pin may be substituted for the nut *i*.

20 Upon each of the radial arms 11, near their outer ends, a sheave block *m* is loosely secured, and the means of attachment is a swiveling connection, as shown for one block in Fig. 6, consisting of a screw-eye bolt *m'* that is hooked into an eye on a swivel bolt *m''*, held to rotate 25 in the top of the block *m*.

Assuming that the head block 10 and hanger arms 11 are secured in proper position on a ceiling A, as indicated in Figs. 1 and 5, the hanger-bars 19 are therewith connected by four cords 20, as shown in Fig. 1. Each 30 cord or small rope 20 is secured by one end upon an end of a respective bar 19, and thence is extended upward to engage the sheave block *m* immediately above said bar 19, over the sheave of which it is passed, and thence is extended horizontally to have its remaining end 35 secured upon a union ring *n*. It will be noted in Fig. 1 that each cord or rope 20 is extended from a sheave block *m* directly toward and into engagement with the ring *n*, and upon said ring is also secured one end of a draft rope 20^a which is extended from the union 40 ring to engage a swiveling sheave block *o* similar to the one shown in Fig. 6. The sheave block *o* is held by a screw-eye or equivalent means upon a side wall or other stable support at a convenient point near the drier, and from said block the rope 20^a hangs pendent 45 alongside of the wall for convenient manipulation.

It will be seen that the cords 20 are so proportioned in length as to adapt them to support the drier frame, that is mainly composed of the radial arms 18, and their central support in a horizontal plane, so that when this 50 frame is lowered to a convenient point, clothing or other goods to be dried may be placed on the arms 18.

After the goods that are to be aired or dried have been hung on the arms 18, the draft rope 20^a is pulled upon, which will correspondingly elevate the drier frame and

fabric hung thereon, thus transferring the drier and 55 goods to a point near the ceiling A, which will expose the damp material to the heat that rises to the upper portion of a room, facilitating the drying of the same, it being understood that the rope 20^a is secured upon any suitable projection on the side wall for retention of the 60 drying frame in an elevated position.

When the drier device is not needed for use and is to be removed from its suspended position, the several parts may be readily folded together in a compact bundle and can be stowed away without taking up much 65 space.

It is claimed for the improvement that it may be maintained in an elevated position in a room, or on a porch under cover, avoiding interference with the free movement of persons in the room, and be ready for 70 service at any time by lowering the frame and subsequently raising the same.

The improved drier is available for the support of laundry clothing or other household linen or the like, when, owing to inclemency of the weather, it is not 75 possible to hang washed goods out in the open air; and it is manifestly of equal advantage as a support for airing and drying freshly ironed fabric, or such as has become damp from any other cause.

Having thus described my invention, I claim as new 80 and desire to secure by Letters Patent:—

1. In a clothes-drier of the character described, the drier frame comprising a central hub, a lower clamping plate thereon, an upper clamping plate, a radial flange on the hub on which the clamping plates are imposed, a 85 plurality of clamping bolts holding the plates clamped on said radial flange, a peripheral flange concentric with the hub and depending from the edge of the upper clamping plate, said peripheral flange having a plurality of spaced openings therein, an equal number of fabric-supporting 90 arms inserted in said openings, and a depending concentric flange on the upper clamping plate, which enters a notch in each of said arms, the arms being held by the last named flange from displacement longitudinally when the same are clamped between the plates.

2. In a clothes drier, the combination with a hub having an enlarged lower end, radial arms secured to the enlarged lower end of the hub, right angled bars on the upper end of the hub, said bars resting one upon the other, and a bolt passed through the hub and said bars.

3. In a clothes drier, the combination of a block having grooves arranged at right angles to each other, one groove being double, the depth of the other, hanger bars arranged in the grooves of the block, and a threaded hanger bolt passed through the block and bars and projecting beyond the said bars to adapt it to be screwed into a wall or ceiling.

In testimony whereof I have signed my name to this specification in the presence of two subscribing witnesses.

ERNEST ARTHUR THORNTON.
